UNITED STATES PATENT OFFICE.

FRANÇOIS EUSTRATIUS MAVROGORDATO, OF CONSTANTINOPLE, TURKEY.

HYDROCARBON-LIGHTING APPARATUS.

SPECIFICATION forming part of Letters Patent No. 758,087, dated April 26, 1904.

Application filed November 12, 1901. Serial No. 32,021. (No model.)

To all whom it may concern:

Be it known that I, FRANÇOIS EUSTRATIUS MAVROGORDATO, a subject of the King of Italy, and a resident of Constantinople, Turkey, have 5 invented a new and useful Hydrocarbon-Burner, of which the following is a specification.

The invention relates to a vaporizing-burner for hydrocarbon in which the oil is fed to the 10 vaporizing portion by air-pressure; and the invention consists in the details of construction and arrangement of parts hereinafter described, and particularly pointed out in the claim.

15 The invention is illustrated in the accompanying drawings, in which—

Figure 1 is a central vertical section through the burner and oil-reservoir, and Fig. 2 is a similar view showing the burner as embodied 20 in a street-light.

Referring more particularly to the figures, O represents a reservoir for the hydrocarbon, and L an air-pipe for conveying air under pressure to a point above the surface of the 25 oil from any suitable source, such as a tank G in Fig. 2. Above the reservoir is located a pipe or tube P, which is secured to the reservoir by a suitable threaded coupling P'. A pipe or tube leads from the tube P to near 30 the bottom of the reservoir. Within the tube P, I locate a plurality of wires S, which divide the hydrocarbon up into a plurality of fine streams, and thus assist in its vaporization. The upper end of the tube P is closed by a 35 plug T, which is preferably made solid and of heat-conducting material, so as to gather the heat from the flame of the burner and transmit it to the tube P. From the upper end of the tube P a small pipe p leads through 40 the wall of said tube and then downwardly and again laterally, where it is connected to a supplemental vaporizing-tube Q, which is closed at its upper end and at its lower end is provided with a removable cap U, having an 45 opening through which passes an inner tube q. This inner tube extends nearly to the top of the supplemental vaporizing-tube and also extends to a suitable distance below the plug U, where it is provided with a nozzle or tip. 50 A removable cap u is provided for permitting the tip to be cleaned. I prefer to provide a plurality of wires in the space between the

supplemental vaporizing-tube and the pipe or tube q, as indicated at S', to further assist in the vaporization of the oil. I also prefer to 55 extend the pipe p outward beyond the tube Q, as indicated at p', and close the end by a removable screw-plug p², whereby the tube may be readily cleaned. Supported by the horizontal portion of the pipe is a burner-tube V, 60 which is preferably made in sections, as shown. At its upper end it is provided with a perforated diaphragm Y and may carry any suitable incandescent mantle, as indicated in dotted lines. At the lower end, which is preferably enlarged, it is provided with openings R, and a rotatable collar W is provided with corresponding openings, so that by rotating the collar the amount of air admitted through the opening may be varied as desired. 70

In order to start the burner, an annular cup Y is placed around the main vaporizing-tube P, which is filled with any suitable absorbent material, so that by filling the cup with alcohol or the like and igniting it the main tube 75 may be initially heated to start vaporization of the hydrocarbon.

Having thus described my invention, what I claim is—

In a vapor-burner a suitable reservoir, an 80 initial vaporizing-tube carried thereby, initial heating means in proximity to said tube, a burner-tube supported in proximity to said initial vaporizing-tube, a supplemental vaporizing-tube located centrally of said burner-tube 85 and having a pipe connection with the initial vaporizing-tube, said supplemental tube having a closed upper end, a vapor-delivery pipe extending from said upper end downward through the tube to the lower part of the 90 burner-tube and provided with a suitable injector-nozzle, means located within the main and supplemental vaporizing-tubes for subdividing the hydrocarbon flowing therefrom and adjustable means for admitting varying quantities of air to the lower end of the burner-tube, substantially as described. 95

In witness whereof I have hereunto set my hand in presence of two witnesses.

FRANÇOIS EUSTRATIUS MAVROGORDATO.
